(57) **CLAIM**

The ornamental design for a level gauge for container, as shown and described in the drawings appended hereto.

DESCRIPTION

FIG. 1 is superior perspective view of the level gauge for container;

FIG. 2 is a frontal elevation view of the level gauge for container;

FIG. 3 is a side elevation view showing the profile of the level gauge for container;

FIG. 4 is a rear elevation view of the level gauge for container;

FIG. 5 is a top view of the level gauge for container;

FIG. 6 is a bottom view of the level gauge for container;

FIG. 7 is a superior perspective view of the level gauge for container disposed within a container; and,

FIG. 8 is a side elevation view of the level gauge for container in the container of FIG. 7.

The portions shown in dotted lines in FIGS. 1, 2, 4, 5, 6, 7 and 8 are environmental only and form no part of the claimed design.
